UNITED STATES PATENT OFFICE.

GEORGE W. GOETTING, OF ROCHESTER, MINNESOTA.

CHECK-WRITER.

1,358,146.

Specification of Letters Patent. Patented Nov. 9, 1920.

Application filed August 14, 1919. Serial No. 317,423.

To all whom it may concern:

Be it known that I, GEORGE W. GOETTING, a citizen of the United States, residing at Rochester, in the county of Olmsted and 5 State of Minnesota, have invented certain new and useful Improvements in Check-Writers, of which the following is a specification.

This invention relates to check writers 10 and its primary object is to produce a check writer which will be simple in construction, cheap to manufacture, accurate and efficient in operation and by means of which a check will be written or printed in such a manner 15 that it will be adequately protected against unauthorized raising.

Another object of this invention is to provide a check writer having a series of printing cylinders with mechanism by which the 20 cylinders will be speedily and accurately moved into printing position to present the desired printing characters in opposition to the platen by movement of a handle in one direction and which will be automatically restored to a neutral position upon movement of said handle in the opposite direction.

Another object of my invention is the 25 provision of a novel and effective mechanism for moving each of the printing cylinders from a common moving member and the provision also of improved mechanism by which the extent of movement of each cylinder may be variably regulated and controlled.

A further object of the invention is to 30 provide novel printing characters on each cylinder which will lacerate the paper check so that the characters and figures printed thereby cannot be raised or changed, and 35 also to provide a platen and novel mechanism for actuating the same whereby the platen is brought into co-operative or printing relation with the printing characters at the proper time.

Other objects of my invention and many 40 of its inherent advantages will be readily appreciated as the same becomes better understood by reference to the following description when considered in connection with

the accompanying drawings. Referring to the drawings,

Figure 1 is a plan view of a check writer embodying my invention;

Fig. 2 is a horizontal sectional view showing the mechanism lying below the keys;

Fig. 3 is an end elevation looking at the right hand end of the machine shown in Figs. 1 and 2;

Fig. 4 is a transverse sectional view through the machine;

Fig. 5 is a longitudinal sectional view on a vertical plane passing through the printing cylinders; and

Fig. 6 illustrates a check written by my improved machine.

By reference to the drawings, it will be observed that the machine comprises essentially a rectangular frame or box consisting of the front and back walls 7 and 8, end 70 walls 9 and 11, bottom 12 and top plate 13. Within this box-like structure is mounted the operating mechanism of the machine with the exception of the keys designated generally by reference character 14 which 75 project above the top 13 as shown in Figs. 1 and 4.

Referring first to the printing cylinder mechanism, it will be observed that near the front wall 7 of the main frame there is rotatably mounted a longitudinally extending shaft 15. Upon this shaft preferably in contiguous relation to each other, are mounted a plurality of printing cylinders indicated by reference characters 16, 17, 18, 80 19, 21 and 22 respectively, which cylinders are maintained in position longitudinally of the shaft by a collar 23 secured to the shaft by a set screw 24. The shaft 15 is preferably made of fibrous material, or it 85 may be made of metal covered with a composition which will afford considerable resistance or friction between itself and the printing cylinders which are rotatably mounted thereon. The purpose of the frictional resistance between the shaft and the printing cylinders is to cause the cylinders to turn with the shaft upon rotation thereof, but as the cylinders must turn variable distances while the shaft always turns a 90 95 100

uniform distance, this frictional connection is employed, which, when any cylinder is held against further rotation, will permit a slippage between such cylinder and the rotating shaft. To insure the desired friction between the cylinders and the shaft, I have provided a strong resistance between each cylinder and the shaft. One preferred form of such friction connection is illustrated in Fig. 4 wherein the cylinder is shown as provided with a socket to receive a friction block 25 and a spring 26 disposed behind the block so as to hold both the block and the cylinder in intimate contact with the shaft. These blocks are also preferably made of frictional material so that adequate frictional resistance between the shaft and each cylinder is afforded to insure rotation of the cylinders with the shaft when the cylinders are free to move therewith. Other means for insuring this desired friction such, for instance, as flat springs, might be utilized, if preferred.

Each of the printing cylinders is provided on an arc of its periphery with suitable printing characters. Cylinder 16, for instance, is adapted to print "one hundred," "two hundred," etc., up to "nine hundred"; cylinder 17 prints "eleven" to "nineteen" inclusive, cylinder 18 prints "ten" to "ninety" inclusive, cylinder 19 prints "one" to "nine" inclusive; cylinder 21 prints the words "Dollars" followed by figures "1" to "9" inclusive; and cylinder 22 prints figures "1" to "9" inclusive followed by the word "Cents." Each cylinder therefore carries nine lines of printing characters and each cylinder also carries a tenth line which simply prints a series of \$ signs, so that if any particular cylinder is not utilized in printing the corresponding space on the check beneath this cylinder will bear these \$ signs. The lines of printing characters are indicated generally in Figs. 2 and 4 by reference character 27.

The printing cylinders are shown in neutral position in Figs. 2 and 4, and to dispose the printing characters in printing position directly beneath the vertical axis of the shaft 15 the cylinders are rotated in a counter-clockwise direction (viewed in Fig. 4) by means of a handle 28 carried by an arm 29 fixed on the shaft 31 extending longitudinally of the machine, through a train of gears consisting of a gear wheel 32 on the shaft 31, an idler 33 and a gear wheel 34 on the shaft 15. The handle 28 is pulled toward the operator, or in other words, swung in a counter-clockwise direction (viewed in Fig. 3) three-eighths of a turn in order to accomplish this result. The train of gears is so proportioned that a three-eighths turn of the shaft 31 imparts approximately three-quarters of a turn to the shaft 15 and the printing cylinders would therefore all be turned three-quarters of a revolution at each

actuation of the handle if provision were not made to limit their rotating movement. The periphery of each cylinder is provided near one end therefore with a groove 35 (Fig. 4) the ends of which groove form abutment shoulders 36 and 37. In each of these grooves there is disposed a fixed stop 38 carried by a bar 39, these bars being supported at each end upon rods 41 and 42 respectively, extending longitudinally of the machine. Upon movement of the handle 28 to the left therefore the cylinders will all rotate in a counter-clockwise direction with the shaft 15, and if the movement is not limited by the key actuated stops which will be later explained, each cylinder will rotate until its shoulder 37 engages its stop 38 whereby its rotating movement will be arrested. Each of the cylinders when arrested by the stop 38 will have its line of \$ signs disposed in printing position so that if a check were printed with the cylinders in this position nothing but a row of \$ signs would appear thereon.

In order to bring the desired line of printing characters on each cylinder into position so that the desired data will be printed on the check, I have provided mechanism by which the rotating movement of each cylinder may be arrested in any desired position. This mechanism consists of a plurality of rows of keys 14 disposed above the respective printing cylinders, as shown in Fig. 1. Each of these keys is mounted upon a bar 43 pivoted at its forward end upon the rod 42 and each bar carries at its rear end a downwardly depending shoulder 44. The periphery of each cylinder is cut away throughout a portion of its surface so as to leave a series of abutments or stops on each cylinder indicated on Figs. 2 and 4 by reference characters *a*, *b*, *c*, *d*, *e*, *f*, *g*, *h*, *i*, *j*. Should it be desired to print with cylinder 21 "Dollars 3" as in printing the check illustrated in Fig. 6, for instance, key numbered 6 in the fifth row would be depressed and its shoulder 44 would thereby be disposed in the path of the shoulder *f* on cylinder 21. Upon rotation of the cylinder in a counter-clockwise direction engagement of the shoulder *f* with the shoulder 44 would stop this cylinder with the desired characters in printing position. The shaft 15, however, would continue its full stroke, imparted to it from the handle 28, since the frictional connection between the shaft and the cylinder permits of relative movement between these members under such circumstances. In printing a check such other key in each row would be depressed as would be necessary to cause the desired printing, and all of the cylinders would be simultaneously moved by the shaft until arrested by their respective stops, and in case no key were actuated for any particular cylinder this cylinder would continue to rotate until arrested by its shoulder 37, in

which position it would print merely the \$ signs. It might be mentioned at this point that cylinder 22 has one extra shoulder, one extra line of printing consisting of zero followed by the word "cents" and an extra key indicated in Fig. 1, reference character 45, which key carries a zero. This cylinder therefore has ten stops or shoulders and ten lines of printing characters, while the other 10 cylinders have nine shoulders and ten lines of printing characters, the last line on each of these cylinders consisting merely of \$ signs.

It will be manifest from Fig. 4 that the 15 stops 37 on the various cylinders will be brought into engagement with their respective stop 38 to arrest further movement of the cylinders before the shaft 15 has completed a three-quarter turn. Additional 20 movement of this shaft after movement of the cylinders has ceased is utilized to perform the printing operation. The platen in this machine consists of a flat platen 46 pivoted at its rear end upon a rod 47 and 25 normally held down at its forward end by a tractile spring 48 against the surface of a cam 49 mounted upon a shaft 51 which is driven from the shaft 15 through a gear 52 on the shaft 15, meshing with a gear 53 on the shaft 51. The front wall 7 is provided 30 with an elongated slot or opening 54 through which a check shown in dotted lines and indicated by 55 may be inserted into the machine between the platen 46 and the 35 printing cylinders. A pair of adjustable stops 56 on the platen serve to limit the insertion of the check and the adjustability of these slots permits the machine to be accommodated to checks of different dimensions, and when the stops are adjusted for 40 a check of a predetermined size the line upon which the printing is to appear will always be disposed in proper position beneath the cylinders when the top edge of 45 the check is abutted against the stops 56. After the check has been positioned as just explained, the handle is swung to the left (viewed in Fig. 3) as previously explained, bringing the printing cylinders into proper 50 printing relation. After the cylinders have all been stopped in their rotation so that they are standing still, continued movement of the shaft 15 brings the high part of the cam 49 beneath the platen and pushes the 55 platen upwardly forcibly against the printing characters on the cylinders, thus effecting the printing operation. Upon return movement of the handle the printing cylinders begin to rotate in a clockwise direction 60 as soon as the pressure of the platen is initially released, and this movement serves to throw the check out of the machine. As return movement of the handle continues, the platen is lowered and all of the cylinders 65 are turned in a clockwise direction until

the stops 36 engage the stationary limiting stops 38, whereupon all of the cylinders are stopped in neutral position.

The printing characters on the printing cylinders consist in my invention of a series of relatively small dots which will perforate the paper of the check and deposit the ink in these perforations so that the alteration of the check is obviated, since the texture of the paper is considerably lacerated by the multiplicity of dots from which the printing characters are made up. In order to facilitate the laceration of the check, the upper surface of the platen is also preferably knurled or roughened.

Ink is applied to the printing characters at each actuation of the cylinders by an ink roll 57 rotatably mounted just forwardly of the cylinders and in contact therewith, as best shown in Fig. 4. Ink may be applied 85 to this roll in any preferred manner, and if desirable an ink fountain of any well known or preferred construction may be applied to the machine.

In order to restore the keys to normal position after each printing operation, I have provided a restoring mechanism consisting of a bar 58 extending longitudinally of the machine just beneath the bars 43 and pivoted near the extremity of each of its forwardly turned ends upon a bolt 59. Downward rocking movement of this bar is limited by stops 61 projecting inwardly from the end walls of the frame or cabinet. Near the center this bar 58 is equipped with a forwardly projecting finger 62 disposed in the path of a dog 63, pivoted at 64 upon an arm 65 mounted upon the shaft 31 and normally held in the position shown in Fig. 4 by the coöperative action of a stop 66 and a tractile spring 67. Upon movement of the shaft 31 in a counter-clockwise direction (viewed in Figs. 3 and 4), the dog 63 as its extremity engages the end of the finger 62, will swing upon its pivot against the force of the spring 67 and thus pass the finger. Upon reverse restoring movement of the shaft 31, however, this dog will engage beneath and elevate the finger 62, thus raising the bar 58 beneath the depressed bars 43, thereby lifting all of these bars and restoring them to normal position. Since the bars 43 are made of relatively light material and are mounted on the rod 42 between resilient spacing elements 68, the friction between these elements and the bars is sufficient to maintain them in their normal elevated position.

In the operation of my improved machine the check to be printed is first inserted in the opening 54 against the stops 56. The handle 28 is then swung forwardly from its normal position, which movement through the gear train rotates the shaft 15 carrying with it the printing cylinders which con-

tinue their rotation until stopped by a shoulder 44 of a depressed key 14 or by the fixed stop 38. During the rotating movement of the cylinders the ink is applied to the printing characters and after the cylinders have been stopped the platen is lifted by the cam 49 to perform the printing operation. Upon reverse movement of the handle the platen is lowered, the cylinders 10 are revolved to neutral position and the key bars 43 are restored to normal elevated position. The frictional connections between the various printing cylinders and the shaft 15 permit the operation of all the cylinders 15 from a single shaft and insure that these cylinders will be disposed in proper printing position.

It is believed that my invention in one of its preferred forms will be understood 20 and many of its advantages appreciated from the foregoing without further description, but it should be manifest that the invention is not limited by the details of construction shown and described but is 25 capable of considerable modification and variation without departing from the essence of the invention as defined in the appended claims.

I claim:

30 1. In a check writer, the combination of a cylinder shaft, a plurality of printing cylinders co-axially mounted upon said shaft and frictionally connected therewith, each of said cylinders being provided on its 35 periphery with a series of printing characters and a series of stops, a power shaft, driving connection between said power shaft and said cylinder shaft, stationary means for limiting the rotation in each direction 40 of each of said cylinders with said cylinder shaft, a series of pivotally mounted keys disposed above each of said printing cylinders, said keys being equipped with shoulders, all disposed in a common radial plane 45 and adapted to be depressed into the path of movement of said stops on said cylinders to limit the rotative movement of said cylinders with said cylinder shaft, and means actuated from said power shaft for restoring 50 all of said keys to normal position.

2. In a check writer, the combination of a cylinder shaft, a plurality of printing cylinders mounted thereon and frictionally connected therewith, each cylinder being 55 provided upon its periphery with a series of printing characters and a series of stops, a group of keys pivotally mounted above each of said cylinders, each key being provided with a depending shoulder, and all of said 60 shoulders being disposed in a plane extending longitudinally of the axis of said shaft, a power shaft, driving connections between said power shaft and said cylinder shaft, key restoring mechanism adapted to be ac-

tuated from said power shaft, and a platen 65 co-operating with said printing cylinders.

3. In a check writer, the combination of a cylinder shaft, a plurality of cylinders mounted thereon, a frictional driving connection between said shaft and each of said 70 cylinders, a series of stops arranged upon the periphery of each of said cylinders, a series of keys corresponding in number to said stops pivotally mounted above each cylinder, said keys being equipped with depending shoulders, all arranged in alinement longitudinally of said cylinder shaft, stationary means for limiting the movement of said cylinders in both directions with 75 said cylinder shaft, a power shaft, driving connections between said power shaft and said cylinder shaft, a platen, a platen actuating shaft, and driving connections between said platen actuating shaft and said cylinder shaft whereby said platen is actuated after said cylinders have completed 80 their movement with said cylinder shaft.

4. In a check writer, the combination of a cylinder shaft, a plurality of printing cylinders mounted thereon and frictionally connected thereto, a series of stops disposed upon the periphery of each of said cylinders, a series of keys for each of said cylinders provided with shoulders adapted to be engaged by said stops, said shoulders being arranged in alinement longitudinally of said shaft, a power shaft, driving connections between said power shaft and said cylinder shaft, and means actuated by said power shaft for restoring said keys to normal position with their shoulders outside the path of movement of said stops.

5. In a check writer, the combination of a rectangular frame, a power shaft extending longitudinally of said frame and near one side thereof, a cylinder shaft mounted in said frame parallel with said power shaft and at the opposite side of said frame, a plurality of printing cylinders frictionally mounted on said cylinder shaft, each cylinder being provided with circumferential printing characters and circumferentially disposed stops, a series of key members pivotally mounted above said power shaft and extending over each of said cylinders, each key member being provided with a depending shoulder, a key mounted on each key member and projecting above the top of said frame, driving connections between said power shaft and said cylinder shaft, a pivotally mounted key restoring device, and means mounted on said power shaft for actuating said restoring device upon movement of said power shaft in one direction only.

6. In a check writer, the combination of a shaft, a plurality of printing cylinders mounted thereon, means including a spring

for frictionally connecting said cylinders to said shaft, a series of stepped shoulders on each cylinder, a series of key actuated stops adapted to be projected into the paths of said shoulders on each cylinder, an operating handle, a platen, a cam for actuating said platen, a key restoring device, and connections between said handle and said mechanisms whereby upon movement of the han-

dle in one direction, the printing cylinders 10 are moved into the desired printing relation and the platen is then moved into printing position and, upon reverse movement of the handle, the platen, cylinders, and key actuated stops are all restored to normal position. 15

GEORGE W. GOETTING.
